UNITED STATES PATENT OFFICE.

LEVON S. SHONT, OF NEW YORK, N.Y.

BATH-STRAP.

1,334,716.

Specification of Letters Patent. Patented Mar. 23, 1920.

Application filed July 29, 1919. Serial No. 314,001.

To all whom it may concern:

Be it known that I, LEVON S. SHONT, a citizen of the United States, residing at New York, in the county of New York and State 5 of New York, have invented certain new and useful Improvements in Bath-Straps, of which the following is a specification.

This invention relates to a bath strap or body rubbing device and an object of the invention is to provide a simple bath strap made of relatively rough permeable material by means of which strap a person may clean and massage his body, at the same time, the strap being particularly designed 10 for use in cleaning and massaging the shoulders and back of a person which are ordinarily inconvenient to reach.

Another object of the invention is to provide a bath strap as specified which is provided with a pocket intermediate its ends adapted to contain detergent material, such as soap, the lather from which, created during the rubbing action with the bath strap, passes through the permeable material of 25 which the strap is formed and thereby may be applied to the body of the person using the device; and further to provide a non-elastic strip which extends longitudinally through the bath strap, and has its ends 30 looped to form handles or finger grips for the strap, which non-elastic strip will prevent stretching of the strap and will permit the holding of the strap flat and tight against the body of the user.

35 Other objects of the invention will appear in the following detailed description taken in connection with the accompanying drawing, forming a part of this specification and in which drawing:

40 Figure 1 is a perspective view of the improved bath strap.

Fig. 2 is a longitudinal section through the bath strap, and

45 Fig. 3 is a cross section through the bath strap showing the soap or detergent material retaining pocket.

Referring more particularly to the drawings, 1 indicates the main body of the bath strap, which is composed of a pair of layers 50 2 and 3 of permeable material, such as wool cotton fabric, or material analogous to that of which bath towels are made, it being woven or knitted to provide ridges indicated at 4 which extend transversely across the 55 outer surfaces of the sections 2 and 3 of the bath strap. These ridges are provided to

permit the proper massaging action as well as the cleaning action of the bath strap during use. The sections 2 and 3 of the bath strap are stitched together along their edges, 60 as indicated at 5 and they are each provided with a slightly enlarged portion intermediate their ends. On one edge of these enlarged portions, the stitching terminates, leaving an open space 6 to allow the insertion of a bar of soap indicated at 7 into the pocket 8 formed between the enlarged portions of the sections 2 and 3. This pocket will permit the use of fine or small pieces of soap, flake soap, or any other suitable detergent material and during operation or use of the bath strap, the lather from the soap will pass through the sections 2 and 3 and be applied to the body of the user by the outer roughened surfaces of the sections 2 65 and 3. In case the outer surface of one section becomes free of lather which is apt to occur owing to the fact that the rubbing action will have a tendency to force the lather through the section outwardly of the body, 70 the strap can be turned over for applying the lather upon the body of the user.

A non-elastic strip 8 extends longitudinally of the bath strap body 1 and it is preferably made of cotton braid or similar permeable material. The strip 8 has its ends looped to form loops 9, adapted to receive the fingers or thumbs of the user to permit the drawing of the bath strap back and forth across the body of the user. The 85 looped ends are stitched to the main body of the strip 8 and also the sections 2 and 3. The strip 8 is stitched to the sections 2 and 3 at longitudinally spaced intervals as shown in Fig. 2 of the drawings.

90 Changes in details, may be made without departing from the spirit of this invention, but;

I claim:

1. As a new article of manufacture, a 100 bath strap composed of a pair of layers of permeable material each provided with transversely extending ridges on its outer surface, said sections provided with enlarged portions intermediate their ends, the 105 sections being stitched together about their edges and having the edges of the enlarged portion at one side free from stitching to permit the insertion of detergent material between the sections at the enlarged portion. 110

2. As a new article of manufacture, a bath strap comprising a pair of sections of per-

meable material, transversely extending ridges formed upon the outer surfaces of said sections, a narrow non-elastic strip extending longitudinally of said sections at their centers and being stitched thereto at spaced intervals between the facing sides of the sections, the ends of said non-elastic strip being looped and stitched to the sections.

3. As a new article of manufacture, a bath strap comprising a pair of sections of permeable material, transversely extending ridges formed upon the outer surfaces of said sections, a narrow non-elastic strip ex-

tending longitudinally of said sections at their centers and being stitched thereto at spaced intervals between the facing sides of the sections, the ends of said non-elastic strip being looped and stitched to the sections, said sections provided with enlarged portions intermediate their ends, said sections being stitched together in such manner as to form a pocket between said enlarged portions to permit of the insertion of detergent material therein. 15 20
